ERIC BRYAN WILLIAMSON, OF BROMLEY, ENGLAND.

MEANS FOR DISPLAYING STAIR COVERINGS.

Application filed April 10, 1925. Serial No. 22,229.

To all whom it may concern:

Be it known that I, ERIC BRYAN WILLIAMSON, a subject of the King of Great Britain, residing at Bromley, in the county of Kent, England, have invented Improved Means for Displaying Stair Coverings, of which the following is a specification.

This invention relates to improved means for displaying stair coverings.

10 When patterns of stair carpets or the like are being shown to customers it frequently happens that the customer desires to see the pattern laid on a stairway in order that he may judge of the effect when laid. This necessitates detaching the pattern from the demonstration frame on which it is mounted and laying it on a stairway and much time and trouble are expended in so doing.

20 The object of the present invention is to provide means whereby a number of patterns of stair coverings may rapidly and easily be displayed in turn, laid upon a portion of a stairway, so that the customer may at once judge of their effect when so laid.

According to the invention a strip, formed 30 of a number of patterns of stair coverings joined together, is drawn by suitable means over a short stairway and is caused to assume a step formation.

The strip may for example be given the step formation by passing it under the stair rods and over the stair treads, and in order to facilitate the movement of the strip over 35 the display apparatus the supports or guides for the strip are preferably in the form of freely rotating rollers.

40 Alternatively the stair treads may be pivotally mounted so as to move into an oblique position during the travel of the stair covering, the covering being thereby permitted to travel in a substantially straight line over the stairway, in consequence of which the tractive effort required to move the strip is 45 reduced. The stair rods are carried upon the pivoting tread so that the said tread is moved about its pivot as soon as the strip of stair covering is placed under tension preparatory to moving over the short stairway.

50 Means may be provided for reversing the direction of travel of the strip over the stairway at any desired moment.

The invention is illustrated by way of example in the accompanying drawings in which—

Fig. 1 is a side elevation of one form of display apparatus,

Fig. 2 is a sectional plan view on the line A—B of Fig. 1,

Fig. 3 is a front sectional elevation on the line C—D of Fig. 1,

Fig. 4 is a side elevation of an alternative construction,

Fig. 5 is a partial plan view of Fig. 4, and

Fig. 6 an elevation looking from the right of Fig. 1.

Referring to the drawings, 1 is a strong framework, built up of angle iron for example, in the sides of which are mounted 70 bearings 2 and 3 for carrying a pair of drums 4, 5. These drums are formed with wide flanges 6, 7 and to each drum is secured one end of a strip 8 (Fig. 1), formed of a number of carpet patterns joined together. 9 and 10 are a pair of parallel and rigid supports arranged obliquely across the sides of the structure and these supports carry a number of bearings 11, 12, 13, 14, 75

for rollers 15, 16, 17, 18. These rollers are 80 arranged in positions which correspond to those of the stair rods and the front edges of the stair treads in an ordinary stairway.

If preferred the rollers 15, 16, 17, 18, may be substituted by rods of circular cross section rigidly fixed at appropriate points to the supports 9, 10, said rods being surrounded by easily rotatable sleeves, there being if necessary a number of such sleeves 85 on each rod. Again, the rods 15, 17 corresponding to stair rods may be replaced by 90

rods of triangular cross section resembling stair rods in appearance and provided at the rear with rollers to facilitate the movement of the strip on said rods. When the 95 carpet patterns are being displayed, the strip is drawn from, say, the roller 5, passing round a guide roller 19 carried in bearings 20 on the rear wall of the structure 1 and then travelling substantially horizontally to the roller 18 over which it passes as though over the edge of a stair tread, next round the roller 17 corresponding to a stair rod and so on round rollers 16, 15, and 21 and finally on to the other drum 4.

100 105 While the display apparatus shown has

only two steps or stairs it will of course be understood that any convenient number may be employed.

The motive power for driving the drums 4 and 5 is derived from an electric motor 22 mounted in the bottom of the structure.

The power is transmitted by belt or chain from the motor pulley 23 to a pulley or chain wheel 24 rigidly mounted at one end of a shaft 25 carried in bearings 26 on upright members of the framework. At the end of a shaft 25 away from the pulley 24 is rigidly mounted a small pinion 27 which in turn transmits motion by a belt or chain to a pulley or chain wheel 28 rigidly mounted on a shaft 29 carried in bearings 30. 31 and 32 are two clutch members mounted to rotate freely on shaft 29 and these two members 31 and 32 are provided with pulley or chain wheels 33, 34 which drive, through belt or chain, the drums 5 and 4 respectively. 35 is a clutch member keyed to the shaft 29 so as to rotate therewith, but capable of sliding longitudinally thereon and according as the sliding clutch member 35 is moved along shaft 29 down or up in Fig. 2 so is the drive transmitted to drum 4 or drum 5 and the strip 8 moved across the display apparatus in one direction or the other.

30 Fig. 3 illustrates a simple construction of hand operated clutch mechanism. 36 is a hand lever formed by one arm of a bell crank lever and movable in a suitable quadrant 37 about an axis 38. The other arm 39 of the bell crank lever imparts movement to a rod 40 which in turn is connected to and rocks the clutch operating lever 41. The latter is mounted at its lower end on a pivot 42 carried on the frame work and carries at a point near its centre a pin 43 which engages in a groove formed in the sliding clutch member 35 or in a ring 44 fixed on the member 35. It will readily be understood that by rocking the hand lever 36 between its extreme positions the drive of the electric motor is transferred from one of the drums 4, 5 to the other.

50 When this construction of apparatus is in operation and the strip of patterns has been run through in one direction, the rotation of the winding-on drum must be arrested as the strip would otherwise be torn away from the emptied drum. This operation may be performed manually, but it is preferable to provide means whereby when the strip has run a certain distance the current of the motor is automatically cut off, or the clutch disengaged and moved to an intermediate position so that the shaft 29 rotates idly.

60 Any known arrangement for this purpose may be provided such as a nut sliding along a screwed rod rotating with one of the drums 4, 5, said nut operating to open a switch when the pre-arranged point in its movement along the screwed rod is reached.

In order that the whole of the patterns in the strip may be displayed ends are provided for the strip of a different material, or of patterns which it is not desired to display.

70 It will be understood that the driving arrangement described above is only referred to as an example, and that any convenient method of driving may be employed. An alternative arrangement may comprise a friction wheel rigidly mounted upon a driven 75 shaft arranged between the winding drums, the dimensions of the friction wheel being such that a slight displacement of one end of the driven shaft suffices to bring the friction wheel into contact with a flange of one or other of the winding drums whereby said drum is caused to rotate. The driven shaft carrying the friction disc may be mounted in self-aligning ball bearings, and means such as a hand lever may be provided to 80 enable one end of said shaft to be moved in the frame of the display apparatus for the purpose of disengaging the friction disc from the flange of the winding-on drum to arrest the drive, or of moving it out of contact with the flange of the winding-on drum and into contact with the flange of the other drum to reverse the direction of movement of the strip.

85 If desired, extensions may be bolted to the drum flange, such extensions being of metal or other material suited to the friction drive and not liable to wear rapidly.

90 In the construction illustrated in Figs. 4 to 6 the pattern strip 50 of carpet or other 100 stair covering, in being led from, say, drum 51 to drum 52, is first led over a roller 53 carried in bearings 54 at the upper end of the framework 55 whence it is led preferably horizontally to a roller 56 which is positioned to form the nosing of the top step. Passing over the roller 56 it is next passed between the stair rod 57 and the stair tread 58, over the nosing 59, between the next 105 stair rod 60 and tread 61 and then horizontally to the roller 62 over which it moves before being finally wound on to drum 52.

110 The stair treads 58 and 61 are hinged respectively at 63 and 64 so as to be capable of moving about horizontal axes determined 115 by said hinges into positions inclined to the horizontal as shown in dotted lines in Fig. 4. The stair rods 57 and 60 are carried in holes formed in small lugs 83, upstanding from small plates 84 secured at the ends of the treads 58 and 61, said plates extending slightly over the ends of the treads to limit their downward movement by engaging with side members 65. While the apparatus may 120 of course be power-driven the drawings illustrate a construction adapted to be driven by hand. The shaft 66 carried in bearings 67 at the upper part of the machine carries a hand-operated crank 78 and three toothed 125 sprockets 68, 69 and 70, any one of which 130

may be coupled when desired to the shaft 66 so that said sprocket may be rotated by the crank.

The sprockets 68, 69 and 70 are connected by chains 71, 72, 73 with sprockets 74, 75, 76, adapted to be rotated in conjunction with the drums 77, 51, 52.

By suitably connecting any one of the sprockets 68, 69 or 70 with the shaft 66, the corresponding drum can be driven to wind on the strip of patterns, the unwinding drum being rotated simply by the pull of the moving strip. If the strip is to be wound for example from drum 51 on to drum 52, sprocket 70 is connected with shaft 66, the other two sprockets 69 and 70 on the same shaft being allowed to run freely.

On turning the crank 78 drum 52 is rotated through the medium of chain 72 and sprocket 75 to wind on the strip pulled from drum 51. The latter drum rotates quite freely, its sprocket 76 being connected by chain 73 with freely rotatable sprocket 69.

As soon as a pull is exerted on the pattern strip, that part situated between roller 56 and roller 62 tends to straighten out and if the pull is continued the stair rods 57 and 60 resting on the strip are lifted together with the treads 58 and 61 to the position shown in dotted lines in Fig. 4. This arrangement permits the strip to be moved with a much smaller tractive effort than would be required if the treads were fixed.

When it is desired to view a certain pattern in position, driving is stopped and the strip is pulled down into the stepped formation by the downward movement of the stair treads, the drum 51 running freely on to provide the necessary additional length. Preferably weights 79 are provided on the lower sides of the treads to ensure the complete downward movement of said treads. Provision for varying the weights 79 may be made.

To reverse the direction of movement of the pattern strip, sprocket 69 is disconnected from shaft 66, sprocket 70 connected, and the crank turned in the reverse direction.

An additional drum of patterns such as 77 may be provided if desired. To bring such additional drum into operation the strip between drums 51 and 52 is wound on to drum 51. A piece of canvas or the like which forms the end of the strip nearest roller 52 is disconnected from the first set of patterns, passed over the additional roller 80 and connected to the patterns wound on drum 77. This pattern strip can now be passed backwards and forwards between drums 52 and 77 in the manner described above, the drum 77 being, however, driven

through the medium of sprocket 68. In the arrangement illustrated the chain 71 transmitting the drive to the sprocket 74, of drum 77 moves over an additional sprocket 81 loosely mounted on the shaft of drum 51. It will be readily understood that any number of additional pattern drums 77 may be provided.

I claim:

1. A stair covering displaying device comprising a track formed of fixed surfaces and a movable surface between said fixed surfaces and means adapted to draw a length of stair covering over said fixed and movable surfaces.

2. A stair covering displaying device comprising a track formed of vertical sections and movable sections which normally lie horizontally between said vertical sections, said movable sections being adapted to swing upward to occupy a position substantially bridging the space between the upper edges of adjoining vertical sections.

3. A stair-covering displaying device comprising a stepped track, means adapted to draw a length of stair-covering over said track, a tread portion of said track so pivoted as to be capable of taking up an oblique position, means adapted to return said tread portion to the horizontal position, and means adapted to hold said stair-covering close to said tread portion but to permit of said stair-covering being drawn along said track.

4. A stair-covering displaying device comprising a stepped track, means adapted to draw a length of stair-covering over said track, a tread portion of said track pivotally mounted to turn on an axis near and parallel to the front edge of said tread portion, and a rod lying parallel to the inner edge of said tread portion, and mounted thereon, beneath which rod the stair-covering is adapted to pass freely.

5. A stair-covering displaying device comprising a stepped track, means adapted to draw a length of stair-covering over said track, part of a tread portion of said track pivotally mounted to turn on an axis near and parallel to the front edge of said tread portion, and a rod lying parallel to the inner edge of said tread portion and mounted thereon, beneath which rod the stair-covering is adapted to pass freely.

6. A stair-covering displaying device as claimed in claim 3 wherein the pivoted portion of the tread is so weighted as to return by gravity from the oblique to the horizontal position.

In testimony whereof I have signed my name to this specification.

ERIC BRYAN WILLIAMSON.
